UNITED STATES PATENT OFFICE.

THORNTON G. GRAHAM, OF KENT, AND HENRY F. SCHIPPEL, OF AKRON, OHIO, ASSIGNORS TO THE B. F. GOODRICH COMPANY, OF NEW YORK, N. Y., A CORPORATION OF NEW YORK.

DESIGN FOR A TIRE.

Application filed January 20, 1928. Serial No. 24,952. Term of patent 14 years.

To all whom it may concern:

Be it known that we, THORNTON G. GRAHAM, a citizen of the United States, residing at Kent, in the county of Portage and State of Ohio, and HENRY F. SCHIPPEL, a subject of the King of Great Britain, residing at Akron, in the county of Summit and State of Ohio, have invented a new, original, and ornamental Design for a Tire, of which the following is a specification, reference being had to the accompanying drawing, forming a part thereof.

This application is a continuation in part of our design application Serial No. 19,771, filed November 18, 1926.

Fig. 1 is a plan view showing a portion of a tire having a tread which embodies our new design.

Fig. 2 is a cross-section on the line 2—2 of Fig. 1.

We claim:

The ornamental design for a tire as shown.

HENRY F. SCHIPPEL.
THORNTON G. GRAHAM.
